CAR AXLE LUBRICATOR PLATE

Harry H. Greece, Detroit, Mich.

Application April 17, 1936, Serial No. 74,861

6 Claims. (Cl. 308—88)

This invention relates to railroad car axle lubricating means and in particular to plate type oiling means adapted to be inserted into the journal boxes of railroad cars for assuring constant lubrication of the car axles at all times.

It has been customary to pack and wedge oil or other lubricant saturated waste in the bottom of journal boxes and around the lower portion of railroad car axles to lubricate the said axles.

When railroad cars so lubricated are in service the waste packed around the car axles settles due to the repeated impact and jarring caused when the cars pass over rail joints and the like. The packing and settling of the waste becomes more acute when a car wheel develops even the slightest flat spot. When the waste packs and settles away from the car axles, the axle ceases to obtain sufficient lubricant which causes overheated bearings, hot boxes, expensive repairs and replacements, and undesirable delays in railroad service. To avoid expensive repairs to rolling stock and delays in railroad service, the journal box packing is preferably stirred and the waste and lubricant replenished at frequent intervals along the route of the railroad at a great expense to the railroad companies.

However, the stirring of the journal box packing is often improperly done and the waste and lubricant are not replenished as required because of carelessness of railroad employees. Also, pockets form in the waste due to repeated impact and jarring of the journal box which are impossible to detect from inspection. When pockets form in the waste, the car axle obtains but a fraction of the lubricant required with the result that the bearing and axle become overheated which in turn rapidly dissipates what lubricant the axle was getting, and a hot box with its attendant expense and delay occurs.

In the prior art many devices have been used to hold the waste against the car axle which do not eliminate or alleviate the forming of pockets in the waste and which cannot be readily adapted to the various sizes and shapes of journal boxes. Some attempts to hold the waste against the axle have been such as materially reduce the volume of lubricant and waste carried in the journal box which necessitates more frequent inspections and replenishing of lubricant, both of which are costly to the railroad companies especially in increased payrolls.

The main object of this invention is to provide inexpensive yet positive means for holding lubricant saturated waste against railroad car

axles within the journal box enclosing the car axle.

Another object of this invention is to provide railroad car axle lubricating means adapted to be flexed into journal boxes enclosing car axles either during the construction of the car or later after the car has been in service.

Another object of this invention is to provide a resilient railroad car axle lubricating plate adapted to urge lubricant saturated waste against the car axle.

Another object of this invention is to provide a resilient railroad car axle lubricating means adapted to accommodate itself to various configurations when urging lubricant saturated waste against the car axle to compensate for uneven packing and settlement of the said lubricant saturated waste in the journal box enclosing the car axle.

Another object of this invention is to provide a resilient railroad car axle lubricating plate adapted to urge lubricant saturated waste against the car axle and at the same time form a reservoir for lubricant in the bottom of the journal box enclosing the car axle and the lubricating plate.

Another object of this invention is to provide a spring action resilient car axle lubricating plate having lubricant conveying means therethrough which does not interfere with the spring action or resiliency of the said plate.

Another object of this invention is to provide a railroad car axle lubricating plate adapted to accommodate itself to various configurations when urging lubricant saturated waste against the car axle to compensate for uneven packing and settlement of the said lubricant saturated waste in the journal box enclosing the car axle, the said lubricating plate forming a reservoir for lubricant at the bottom of the said journal box, and the said plate having means therethrough for conveying lubricant from the reservoir so formed to the waste above the said lubricating plate.

Other objects of this invention will become apparent by reference to the following detailed description taken in connection with the accompanying drawings, in which:

Fig. 1 is a longitudinal sectional view of a resilient car axle lubricating plate embodying the invention inserted in a journal box prior to packing waste or other journal packing therein.

Fig. 2 is a cross sectional view taken on the line 2—2 of Fig. 1.

Fig. 3 is a longitudinal sectional view of a resil-

ient car axle lubricating plate embodying the invention inserted in a journal box and compressed to a typical configuration by the packing of waste or other journal packing between the 5 car axle and the said lubricating plate.

Fig. 4 is a cross sectional view taken on the line 4—4 of Fig. 3.

Fig. 5 is a plan view of a car axle lubricating plate embodying the invention.

10 Fig. 6 is an enlarged sectional view taken on the line 6—6 of Fig. 5.

Fig. 7 is a plan view of another embodiment of a car axle lubricating plate contemplated by the invention.

15 Fig. 8 is an enlarged sectional view taken on the line 8—8 of Fig. 7.

Fig. 9 is an enlarged sectional view of a preferred wicking means for conveying lubricant through the embodiment of the car axle lubricating plate disclosed in Figs. 4 and 5.

20 Fig. 10 is an enlarged sectional view of a preferred wicking means for conveying lubricant through the embodiment of the car axle lubricating plate disclosed in Figs. 7 and 8.

25 Referring particularly to the drawings wherein like numerals refer to like and corresponding parts throughout the several views, the embodiment of the invention disclosed in Figs. 5 and 6 is shown in Figs. 1 to 4 inclusive as applied to a 30 car axle 15 which may have a car or the like journaled thereon by means of a bearing 16 suitably secured in the top of the usual journal box 17 by a suitable wedge 18. The journal box 17 is provided with a spring closed hinged lid 19 35 which covers its front opening. A dust guard 20 around the hub seat 21 of the axle 15 seals the rear opening of the journal box 17. The end of the axle 15 is provided with a collar 22. A jack plate 23 is provided on the bottom of the journal box 17 for convenience when jacking up the car 40 and changing its bearings.

The embodiment of the invention disclosed in Figs. 5 and 6 comprises a resilient plate 24 of 45 spring steel or other suitable material having a plurality of substantially uniformly spaced preferably involute springs 25 secured to the bottom thereof by such means as resistance welding, riveting or the like. The said resilient plate 24 is preferably provided with a plurality of apertures 26 therethrough interspersed between the 50 said springs 25.

Oil or other lubricant saturated waste 27 may depend through the apertures 26 provided in the resilient plate 24, see Fig. 3, or, a wicking bat 28 55 may depend through the apertures 26 in the resilient plate 24 as best shown in Fig. 9. The wicking bat 28 is preferably frictionally retained in the desired relationship to the resilient plate 24 by virtue of its size in respect to the diameter of the 60 said apertures 26.

The wicking bat 28 is preferably constructed with alternate long and short pieces of wicking 29 and 30 respectively which permits the lower 65 end of the said bat 28 to flex readily and thereby cause little if any interference with the deflection of the resilient plate 24 when pressure is applied thereon.

In Figs. 1 and 2 a resilient car axle lubricating plate assembly is shown inserted in the bottom of 70 a journal box 17 prior to packing the axle 15 with oil or other lubricant saturated waste. The lubricating plate assembly is best inserted into the said journal box 17 by flexing the plate 24 through the front opening of the said journal box 17 and 75 below the collar 22 of the car axle 15.

After inserting the car axle lubricating plate assembly into the journal box 17, oil or other lubricant saturated waste 27 or the like may be packed in the journal box 17 above the resilient plate 24 around and against the lower portion of 5 the car axle 15 substantially as shown in Figs. 3 and 4.

When packing the axle, the springs 25 on the bottom of the resilient plate 24 compress and the plate 24 flexes in accordance with the uniformity of the pressure exerted on the said 10 flexible plate 24 by the packed waste 27. Any uneven packing or uneven settlement of the waste 27 will cause the resilient plate 24 to accommodate itself to various configurations as indicated in Figs. 3 and 4 and thereby automatically compensate for pockets which may form in the waste 15 27 due to the said uneven packing and/or settlement of the said waste 27. The springs 25 on the bottom of the said resilient plate 24 constantly urge the oil or other lubricant saturated waste 20 27 upward against the axle 15 thereby lubricating the same.

Free oil or other suitable liquid lubricant 31 may be added to the journal box preferably up to a level as indicated by the dot and dash lines 25 32 in Figs. 1 to 4 inclusive. The space between the resilient plate 24 and the bottom of the journal box 17 serves as a reservoir for free lubricant 31 which is fed up to the waste 27 by the capillary attraction of waste which may 30 depend into the said reservoir through apertures 26 in the said resilient plate 24. It is preferable, however, to feed free lubricant to the waste 27 from the reservoir below the resilient plate 24 by the use of such particularly suitable means 35 as the wicking bats 28 depending through the said resilient plate 24, see Fig. 9. Wicking bats 28 constructed as hereinbefore described offer substantially no resistance to the flexing or depressing of the resilient plate 24 and provide 40 positive means for conveying lubricant from the reservoir in the journal box 17 below the resilient plate 24 to the waste 27 when the lubricant in the waste 27 is expanded therefrom by lubricating the axle 15 or by drainage into the reservoir 45 formed below the said flexible plate 24.

Figs. 7 and 8 disclose another embodiment of the invention comprising a resilient plate 33 of spring steel or other suitable material having a plurality of leaf type springs 34 secured to the bottom thereof by such suitable means as the rivets 35. The said resilient plate 33 is 50 preferably provided with a plurality of slotted apertures 36 therethrough interspersed between the said leaf springs 34.

Oil or other lubricant saturated waste 27 may depend through the apertures 36 provided in the resilient plate 33, or, a wicking bat 37 may 55 depend through the apertures 36 in the resilient plate 33 as best shown in Fig. 10. The wicking bat 37 is preferably frictionally retained in the desired relationship to the resilient plate 33 by virtue of its size in respect to the size of the 60 said apertures 36.

The wicking bat 37 is preferably constructed 65 with alternate long and short strips of wicking 38 and 39 respectively which permits the lower end of the said bat 37 to flex readily and thereby cause little if any interference with the deflection of the resilient plate 33 when pressure 70 is applied thereon.

After being inserted in a journal box 17, the embodiment of the invention disclosed in Figs. 7, 8 and 10 functions similarly to the hereinbefore described operation of the embodiment 75

of the invention as shown in Figs. 1 to 6 inclusive and Fig. 9.

Although the use of wicking bats 28 and 37 in combination with resilient plates 24 and 33 respectively is not necessary to the functioning of either of the embodiments disclosed herein, the use of the said wicking bats is desirable and preferable inasmuch as the effectiveness of the car axle lubricating plate assemblies is increased thereby.

Although but two specific embodiments of this invention have been disclosed and described herein, it will be understood that various changes including the size, shape, arrangement and details of the various parts thereof may be made without departing from the spirit of the invention, and it is not intended to limit the scope of the invention other than by the terms of the appended claims.

20 I claim:

1. In combination with a car axle and a journal box having lubricant saturated packing therein for lubricating said car axle, a resilient plate below said packing, and spring means spaced longitudinally and transversely with respect to the said car axle secured to said plate capable of flexing in accordance with the yielding of the said packing adapted to urge said plate upward and maintain said packing in uniform contact with said car axle.

2. In combination with a car axle and a journal box having packing therein, a resilient plate below said packing, a multiplicity of springs secured to the bottom of the said resilient plate on longitudinal and transverse axes with respect to the said car axle adapted to urge said packing with uniform pressure against said car axle and form a reservoir for free lubricant in the bottom of said journal box, the said resilient plate having a plurality of apertures therethrough, and wicking bats formed of alternate long and short pieces of wicking secured to said plate through said apertures and depending into said reservoir.

45 3. In combination with a car axle and a journal box having packing therein, a thin resilient plate assembly having a multiplicity of springs substantially uniformly spaced, both laterally

and longitudinally with respect to the car axle, on the bottom thereof positioned below said packing for urging said packing against said car axle, the said thin resilient plate being of sufficient resiliency to accommodate itself to various wavy configurations and thereby compensate for voids in said packing and the uneven settlement thereof.

4. In combination with a car axle and a journal box having packing therein, a resilient plate 10 capable of flexing in accordance with the yieldability of said packing positioned in said journal box below said packing, and a multiplicity of springs spaced longitudinally and transversely with respect to the car axle on the bottom of 15 the said plate adapted to urge said packing uniformly against said car axle.

5. In combination with a car axle and a journal box having packing therein, a resilient plate capable of flexing in accordance with the yieldability of the said packing positioned in said journal box below said packing, and a multiplicity of springs spaced longitudinally and transversely with respect to the car axle on the bottom of 20 the said plate adapted to urge said plate upward and said packing against said car axle, the said resilient plate having apertures therein through which portions of said packing depend into a reservoir of free lubricant in the bottom of the said journal box, whereby the said free 25 lubricant is conveyed to the said packing in contact with said car axle by capillary attraction.

6. In combination with a car axle and a journal box having packing therein, means for uniformly urging said packing against said car axle comprising a resilient plate and a multiplicity of springs secured in substantially longitudinal and transverse uniform spaced relationship with respect to the car axle on the bottom of the 30 said resilient plate, the said resilient plate being sufficiently flexible to accommodate itself to various wavy configurations when urging said packing against said car axle and thereby compensate for voids in the said packing and any uneven 35 settlement thereof.

HARRY H. GRECE.
